US00D938300S

(12) United States Design Patent (10) Patent No.: US D938,300 S
(45) Date of Patent: * Dec. 14, 2021

(54) PAIR OF EARRINGS

(71) Applicant: Harry Winston SA, Plan-les-Ouates (CH)

(72) Inventor: Delphine Abdourahim, New York, NY (US)

(73) Assignee: Harry Winston SA, Plan-les-Ouates (CH)

() Term: 15 Years

(21) Appl. No.: 29/743,811

(22) Filed: Jul. 24, 2020

(30) Foreign Application Priority Data

Feb. 10, 2020 (WO) WIPO91975

(51) LOC (13) Cl. 11-01

(52) U.S. Cl.

USPC D11/43
